RUBERT A. HULL, OF ANDOVER, ILLINOIS

DESIGN FOR A COMBINATION PORTRAIT MONUMENT

Application filed September 9, 1932. Serial No. 44,789. Term of patent 14 years.

To all whom it may concern:

Be it known that I, RUBERT A. HULL, a citizen of the United States, residing at Andover, in the county of Henry and State of Illinois, have invented a new, original, and ornamental Design for a Combination Portrait Monument, of which the following is a specification, reference being had to the accompanying drawing, forming a part thereof.

Fig. 1 is a front perspective view of the combination portrait monument constituting my new design, the door being shown open.

Fig. 2 is a fragmentary front perspective view of the monument shown in Fig. 1, the purpose being to show the door closed.

The monument consists of an inner and outer case. Through the floor or bottom of the inner one extend two vases, one on either side of a grooved plate for a portrait. Although removable they form an integral part of the design.

I claim:

The ornamental design for a combination portrait monument, as shown and described.

RUBERT A. HULL.
